US00D951955S

(12) **United States Design Patent** (10) **Patent No.:** **US D951,955 S**
Turksu et al. (45) **Date of Patent:** **** May 17, 2022**

(54) **HUB WITH STAND FOR MINI COMPUTER**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA, LLC**, San Diego, CA (US)

(**) Term: **15 Years**

(21) Appl. No.: **29/761,847**

(22) Filed: **Dec. 11, 2020**

Related U.S. Application Data

(63) Continuation of application No. 29/741,905, filed on Jul. 16, 2020, now Pat. No. Des. 907,043, which is a continuation of application No. 29/670,110, filed on Nov. 13, 2018, now Pat. No. Des. 894,191.

CLAIM

What is claimed is an ornamental design for a hub with stand for a mini computer, as shown and described.

DESCRIPTION

FIG. 1 is a front, top, left perspective view of a hub with stand for a mini computer showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Wherein the broken lines depict portions of the hub with stand for mini computer that form no part of the claimed design.

1 Claim, 4 Drawing Sheets
